DUPLICATING MACHINE

Edward L. Brown, Pepper Pike, Ohio, assignor to Addressograph-Multigraph Corporation, Cleveland, Ohio

Filed Sept. 3, 1974, Ser. No. 502,530

Term of patent 14 years

Int. Cl. D18—02

U.S. Cl. D16—27

Fig. 1

Fig. 2

FIG. 1 is a front perspective view of a duplicating machine showing my new design; and

FIG. 2 is a rear perspective view thereof.

The undisclosed bottom of the design is plain and unornamented.

I claim:

The ornamental design for a duplicating machine, substantially as shown.
